The ornamental design for an interlocking paving block, as shown and described.

DESCRIPTION

FIG. 1 is a top plan view of an interlocking paving block showing my new design;

FIG. 2 is a right end elevational view thereof;

FIG. 3 is a right side elevational view thereof;

FIG. 4 is a left end elevational view thereof;

FIG. 5 is a left side elevational view thereof;

FIG. 6 is a bottom plan view thereof;

FIG. 7 is a cross-sectional view taken along line 7—7 of FIG. 1;

FIG. 8 is a cross-sectional view taken along line 8—8 of FIG. 1;

FIG. 9 is a top plan view of a second embodiment of my new design;

FIG. 10 is a right end elevational view thereof;

FIG. 11 is a right side elevational view thereof;

FIG. 12 is a left end elevational view thereof;

FIG. 13 is a left side elevational view thereof;

FIG. 14 is a bottom plan view thereof;

FIG. 15 is a top plan view of a third embodiment of my new design;

FIG. 16 is a right end elevational view thereof;

FIG. 17 is a right side elevational view thereof;

FIG. 18 is a left end elevational view thereof;

FIG. 19 is a left side elevational view thereof; and,

FIG. 20 is a bottom plan view thereof.
